REMOTE CONTROL SYSTEM

Earl M. Allen, Swissvale, Pa., assignor to The
Union Switch & Signal Company, Swissvale,
Pa., a corporation of Pennsylvania

Application August 25, 1938, Serial No. 226,756

10 Claims.

(Cl. 246—3)

My invention relates to remote control systems, and more particularly to remote control systems for railways.

I shall describe one form of apparatus embodying my invention, and shall then point out the novel features thereof in claims.

A feature of my invention is the provision in remote control systems of the type here contemplated of novel and improved means for controlling a plurality of different devices from a remote point and for indicating at the control point the respective positions of such devices. Another feature of my invention is the provision in a system of this character of apparatus to both 15 control a device from a remote point and to continuously indicate at such point the position of the device by virtue of a single two-wire line circuit, one wire of which may serve as a common wire for several such line circuits. Again, 20 a feature of the invention is the provision in a system of this character when it employs sources of current of reversible polarity at both ends of a two-wire line circuit of novel and improved circuit switching apparatus for connecting only one 25 source to the line circuit at a time. When apparatus embodying my invention is applied to the control of railway track switches and signals, an additional feature of the invention is the provision of apparatus for remotely controlling and indicating such track switches and signals wherewith additional line wires, when the number of switches and signals is not balanced, are avoided. Other features and advantages of my invention 30 will appear as the specification progresses.

In the accompanying drawings, Figs. 1a and 1b, when taken together with Fig. 1b placed at the right of Fig. 1a, are a diagrammatic view of one form of apparatus embodying my invention when applied to the control and indication of railway 35 track switches and signals. It will be understood, of course, that I do not wish to limit my invention to the control of railway track switches and signals, but this one use of apparatus embodying my invention will serve to illustrate the many 40 places where the invention will be useful.

Referring to the drawings, the linegraph at the upper right-hand portion of Fig. 1b designates a stretch of double track railway provided with a crossover CV to permit traffic to move between 45 an eastbound track EB and a westbound track WB. The eastbound track EB is formed in the usual manner with a detector track section 2T which extends to the limits of the crossover, and in like fashion the westbound track WB is formed 50 with a detector track section 4T. Each of these

track sections is provided with a track circuit which includes a track relay designated by the reference character R plus a prefix corresponding to the reference character of the section, the relationship of each track relay with its section 5 being indicated by a dash line.

In accordance with standard practice, signals R2 and L2 are located at the opposite ends of the track section 2T for governing traffic through the section, the signal R2 being provided with signal 10 mechanisms R2A, R2B and R2C mounted on a single mast, and the signal L2 being provided with but one mechanism. Signals L4 and R4 are provided at the opposite ends of track section 4T for governing traffic through that section, the signal 15 L4 comprising three signal mechanisms L4A, L4B and L4C mounted on a single mast, and the signal R4 having but one mechanism.

It should be pointed out that signals R2 and L2 form what is commonly referred to as a "right" 20 signal and a "left" signal for governing traffic in opposite directions over a track section having a track switch, and which signals are selectively governed by a single controlling unit. The signal mechanisms R2A and L2 are used when the 25 crossover CV is at its normal position, signal mechanism R2B is used when the crossover is at its reverse position for directing traffic from track EB to track WB, and the signal mechanism R2C is used as a so-called "call-on" signal. 30 Again, signals L4 and R4 form "right" and "left" signals for governing traffic over the track section 4T, which track section is also associated with the track switches of the cross-over CV, signal mechanisms L4A and R4 being used when the 35 crossover is set at the normal position, signal L4B being used when the crossover is set at its reverse position, and signal mechanism L4C being a call-on signal.

In other words, this track layout requires an 40 unbalanced condition between the switch control and the signal control since the track switches of the crossover require but one normal and reverse control, while the associated signals require three such controls, one signal control for 45 the right signals R2A and R2B and the associated left signal L2, a second signal control for the right signal R4 and the left signals L4A and L4B, and a third signal control for the call-on signals L4C and R2C. This unbalanced condition of the 50 related devices (switches and signals) will be referred to later on in the description.

Additional signals would, of course, be provided for governing traffic approaching the signals at the crossover, but such additional signals are 55

not shown since they are not required for a full understanding of my invention.

The signal mechanisms may be of any well-known form, and are shown conventionally for the sake of simplicity.

The two track switches for the cross-over CV are preferably operated by power switch machines SM1 and SM2. The type of switch machine is immaterial, and they are shown by the symbol commonly used to indicate such power switch machines. It is sufficient for the instant application to point out that each switch machine SM1 and SM2 would preferably include a reversible electric motor (not shown) which, when supplied with current of one polarity, is operated to move the associated track switch to one of its extreme positions, and when supplied with current of the opposite polarity is operated to move the switch to its other extreme position, the operation of the two motors for switch machines SM1 and SM2 being made dependent upon each other so that the two ends of the crossover always agree as to position.

Control of the switch machines SM1 and SM2 of the crossover CV and of the associated signals is effected in part from a remote control point CO (Fig. 1a) such as, for example, a dispatcher's office, through the medium of apparatus located partly at the office station CO and partly at a field station FL, which latter station is preferably located adjacent the crossover. Each station CO and FL is provided with a suitable source of current which in this instance is a battery, a battery 12 being located at station CO and a battery 13 being located at station FL. In order that current of normal and of reverse polarity may be supplied, the batteries 12 and 13 are preferably provided each with a positive terminal B1, a negative terminal N1 and a mid or center terminal C.

Referring first to the apparatus located at the field station FL, a polarized relay WR is provided for governing the switch machines SM1 and SM2, the arrangement being such that when the relay WR is energized by current of normal polarity and its front neutral contact 4 and normal polar contact 5 are closed, current is supplied from terminal B1 of the current source over wire 6 to the motor of the switch machine SM1 to move the associated track switch to its normal position, and the circuit is extended over wire 7 to the motor of the switch machine SM2 to move the associated track switch to its normal position. In each case the circuit for the motor is completed to the terminal N1 of the current source over wire 8. When the relay WR is energized with current of reverse polarity and its front neutral contact 4 and reverse polar contact 9 are closed, current is supplied over wire 10 to the motor of the switch machine SM1 for moving the associated track switch to its reverse position, and the circuit is extended over wire 11 to the motor of the switch machine SM2 for operating the associated track switch to its reverse position. The switch controlling relay WR is preferably slow releasing in character, and the control thereof will be described hereinafter.

Before proceeding further with the description, it should be pointed out that contact fingers of the track relays 2TR and 4TR and of the polarized relay WR, as well as of other relays to be later referred to, are for the sake of clearness shown remote from the windings of the relays. In each case the contact finger is identified by the reference character of the relay and is illus-

trated in the position corresponding to the normal energized or deenergized condition of the relay winding. In other instances contact members are shown remote from their operating device, and these contact members are in each case identified by the reference character of the operating device, and each is illustrated in the position corresponding to the normal position of the operating device.

A switch indication relay KR and a repeater relay WKRP are associated with the switch controlling relay WR. The relay KR is a polarized relay energized by current of normal polarity when the track switches of the crossover both occupy their normal positions so that the contact members 34 and 35 operated by machine SM1 and its associated track switch, and the contact members 36 and 37 operated by the switch machine SM2 and its associated track switch occupy the positions illustrated by the solid lines in the drawings, and the normal polar contact 38 of relay WR is closed. Relay KR is energized by current of reverse polarity when the crossover CV is set at its reverse position so that the respective contact members 34, 35, 36 and 37 occupy the positions illustrated by the dotted lines and the reverse polar contact 39 of relay WR is closed. The relay WKRP is energized over a simple circuit including back contact 40 of relay WR in multiple with a back contact 41 of relay KR, a resistance 141 being preferably connected across the winding of relay WKRP to provide the relay with slow release characteristics.

The apparatus at the field station FL is provided with a signal control relay for each of the several signals, such signal control relays being identified by the reference character H plus a prefix corresponding to the reference character of the signal it governs. For reasons to appear hereinafter, the signal control relays for signals L4A, L4B and R4 are omitted from the drawings. The operating circuits for each signal are controlled by the associated signal control relay according to standard practice, and these operating circuits are not shown in order to not unduly complicate the drawings since such operating circuits are well known and they form no part of my present invention. It is deemed sufficient to say that when a signal control relay is deenergized, the associated signal assumes a stop position, and the signal is operated to a proceed position when the signal control relay is energized. For example, the signal control relay R2AH, when deenergized, causes signal R2A to assume its stop position, and, when energized and picked up, it causes the signal R2A to assume a proceed position.

The signal control relays R2AH, R2BH and L2H are controlled by a polarized relay 2HR, since, as pointed out hereinbefore, these signals comprise what is commonly called "right" and "left" signals for governing traffic over the track section 2T, and are selectively controlled by a normal and a reverse control. With relay 2HR energized by current of normal polarity so that its front neutral contact 14 and normal polar contact 15 are closed, the relays R2AH and R2BH are selectively energized according to the position of the crossover CV and in response to traffic conditions in advance of the signal. The circuit for relay R2AH involves battery terminal B1, front contact 14, normal polar contact 15, winding of relay R2AH, a traffic controlled circuit network 16, contacts 17 and 18 operated by the track switches of the crossover CV and closed when

each switch of the crossover occupies its normal position, and battery terminal C. With the crossover moved to its reverse position so that the contact members 17 and 18 occupy the positions illustrated by the dotted lines in the drawings, the relay R2BH is selected, it being assumed, of course, that the traffic controlled circuit network 19 is also closed. Relay 2HR, when energized by current of reverse polarity so as to close its front neutral contact 14 and reverse polar contact 20, governs a circuit for signal control relay L2H, the circuit being completed over contact members 21 and 22 closed with the track switches of the crossover CV in their respective normal positions, and over a traffic controlled circuit network 23. It should be noted that contacts 17 and 18 as well as contacts 21 and 22 may be polar contacts operated by the switch indication relay KR. In other words, the polarized relay 2HR, when energized at normal polarity, selectively controls signals R2A and R2B according to the position of the crossover for governing eastbound traffic operating over track section 2T, and, when energized by current of reverse polarity, it controls signal L2 for governing westbound traffic operating over track section 2T.

Since the signals L4A, L4B and R4, as pointed out hereinbefore, constitute "right" and "left" signals that govern traffic over the track section 4T, which is also associated with the crossover CV, the field station apparatus would include another signal controlling polarized relay similar to the relay 2HR for governing the signal control relays for the signals L4A, L4B and R4, and which polarized relay when energized at normal polarity would selectively control signals L4A and L4B according to the position of the crossover, and when energized with current of reverse polarity would govern the signal R4. This polarized relay and the signal control relays for signals L4A, L4B and R4 are not shown, however, since the control thereof is but a duplication of the control of relay 2HR and its associated signal control relays, and it is thought such duplication of apparatus would only complicate the drawings without adding to the understanding of the invention.

The call-on signals R2C and L4C, which also require a normal and a reverse signal control, are governed through the medium of a polarized relay 2-4CO provided in the apparatus at the field station FL. When the polarized relay 2-4CO is energized at normal polarity, causing its front neutral contact 24 and normal polar contact 25 to be closed, a simple pick-up circuit is formed for the signal control relay R2CH. The signal control relay R2CH is provided with a stick circuit including front contact 26 of the signal control relay R2AH and a front contact 27 of the relay R2CH. Hence, the signal control relay R2CH is operated to clear the call-on signal R2C only if the signal control relay R2AH for signal R2A has first been picked up, the call-on signal R2C being used in the usual manner when the signal R2A has for some reason failed to operate. The polarized relay 2-4CO, when energized at reverse polarity to close front neutral contact 24 and reverse polar contact 28, completes a circuit for signal control relay L4CH for the signal L4C, the relay L4CH being also provided with a stick circuit including front contact 29 of signal control relay L4AH (not shown) and its own front contact 30, so that the call-on signal L4C would be used only if the signal L4A for some reason failed to operate.

It is again pointed out that the track layout shown in Fig. 1b requires an unbalanced condition between the switch control and the signal control because the track switches of the crossover CV require but a single normal and reverse control for governing the polarized relay WR, whereas the associated signals require three such normal and reverse controls, one for governing the polarized relay 2HR which controls signals R2A, R2B and L2; a second such control for governing a polarized relay to control the signals L4A, L4B and R4; and a third such control for governing the polarized relay 2-4CO which controls the call-on signal R2C and L4C.

The winding of each of the polarized relays 15 WR, 2HR and 2-4CO is interposed in a two-wire line circuit extending between the office station CO and the field station FL, the line circuit for relay WR including a control line wire W1 and a common line wire CL, the circuit for relay 2HR 20 including a control line wire W2 and common line wire CL, and the circuit for relay 2-4CO including a control line wire W3 and common line wire CL.

At the field station FL the first mentioned line 25 circuit involves, when the crossover CV is set at its normal position, line wire W1, approach locking circuit contacts 65, 66, 67 and 68, front contacts 69 and 70 of track relays 2TR and 4TR, respectively, winding of relay WR, back contact 71 30 of relay WKRP, normal polar contact 72 of relay KR, and terminal N1 of battery 13, the common line wire CL being connected to the center terminal C of battery 13. In the event the crossover CV is set at its reverse position so that the 35 relay KR is energized at reverse polarity, the above traced line circuit is completed at reverse polar contact 73 of relay KR and the positive battery terminal B1. Consequently, current of normal or reverse polarity is supplied from battery 13 to this line circuit through the winding of relay WR according to the position of the crossover except when a movement of the crossover is to be effected. As will be later pointed out, the current thus supplied to the line wire W1 40 from battery 13 serves to indicate the position of the cross-over CV as well as to energize the polarized relay WR. The approach locking circuits in which the contacts 65 to 68 are controlled would be in accordance with standard 50 practice and are not shown for the sake of simplicity. When conditions are such as to cause in the usual manner the release of one of the approach locking circuit contacts 65 to 68, or when either detector track section 2T or 4T is 55 occupied to cause the release of track relay 2TR or 4TR, the line wire W1 is disconnected from relay WR and the relay WR is retained energized by virtue of a local circuit which is completed at one of the back contacts 74 to 79, inclusive, as will be readily understood from an inspection of Fig. 1b. Again, at such time as the relay WKRP is picked up, closing front contact 80, a connection is completed for this line circuit around the battery 13, the right-hand terminal 65 of the winding of relay WR being now connected directly with the common line wire CL.

The polarized relay 2HR is interposed in the second mentioned line circuit by virtue of the line wire W2 being connected to the left-hand terminal of the winding of relay 2HR and the right-hand terminal of the winding of relay 2HR being connected with the common line wire CL over front contacts 81 and 82 of the respective signal repeater relays L2P and R2P to be re- 75

ferred to later. At such time as the relay L2P is released, closing back contact 103, this line circuit is connected to the positive terminal B1 of battery 13, and when relay L2P is picked up, closing front contact 81, and relay R2P is released, closing back contact 104, this line circuit is connected to the negative terminal N1 of battery 13.

The polarized relay 2-4CO is interposed in the last mentioned line circuit, the left-hand terminal of the winding of relay 2-4CO being connected with the line wire W3, and the right-hand terminal of the winding of the relay being connected with the common line wire CL. These line circuits will be again taken up after the apparatus at the office station is described.

The apparatus of the field station FL also includes two signal repeater relays R2P and L2P for checking the positions of the signals R2A, R2B and L2. The circuit for relay R2P includes back contacts 31, 32 and 132 of the signal control relays R2AH, R2BH and R2CH, respectively. When all three relays R2AH, R2BH and R2CH are deenergized so that the respective signals are at their stop positions, the relay R2P is energized, but when either relay R2AH, R2BH or R2CH is picked up to operate the respective signal to a proceed position, the relay R2P is released. The relay L2P is controlled over back contact 33 of the signal control relays L2H, and is hence energized when relay L2H is deenergized so that signal L2 is at its stop position, and relay L2P is deenergized when relay L2H is picked up to operate the signal L2 to a proceed position. These signal repeater relays R2P and L2P are provided with slow release characteristics and are, for reasons to later appear, each so constructed that, when the relay is released, an interval between the opening of the front contact 40 of the relay and the closing of its back contacts is assured. That is, there is an interval between the opening of front contact 81 of relay L2P and the closing of its back contact 103; and there is a like interval between the opening of front contact 45 tact 82 of relay R2P and the closing of its back contact 104. It is also to be pointed out that relay WKR is adjusted so that a similar interval exists between the opening of the front contact 50 and the closing of its back contact 71.

Referring to the office station apparatus, a switch lever 1L, two signal levers 2L and 4L and two push buttons 2PB and 4PB are mounted for convenient manual operation. As will shortly appear, switch lever 1L is used to govern control current applied from the office station battery 12 to the line circuit including line wire W1 for energizing the polarized relay WR to govern the switch machines SM1 and SM2. The signal lever 2L is used to govern control current applied from the battery 12 to the line circuit including line wire W2 to energize the polarized relay 2HR for controlling the associated signal control relays of the signals R2A, R2B and L2. The signal lever 4L is used in a manner similar to the signal lever 2L for governing the signals L4A, L4B and R4. The push buttons 2PB and 4PB are used to control current supplied to the line circuit including line wire W3 to energize the polarized relay 2-4CO for governing the signals R2C and L4C.

The switch lever 1L comprises a manually operable handle 42 and circuit controlling contact members 43 to 49, inclusive. The handle 42 is capable of moving the lever to a normal position N and to a reverse position R, and the

several contact members are connected with the handle for closing contacts at different positions of the lever. The signal lever 2L comprises a manually operable handle 50 and circuit controlling contact members 51 to 56, inclusive. The handle 50 is capable of moving the lever from a mid or normal position N to either a right position RT or to a left position LT, and the several contact members are connected with the handle 50 for closing contacts at different positions of the lever. The signal lever 4L is provided with three positions, N, LT and RT, the same as the signal lever 2L, and the lever 4L will be again referred to later on. The push buttons 2PB and 4PB are of the spring return type, push button 2PB closing a contact 57 when depressed and the push button 4PB closing a contact 58 when depressed.

In order to at times connect the battery 12 with the line circuit including line wires W1 and CL to energize the polarized relay WR in accordance with the position of the switch lever 1L and at other times to connect this line circuit around the battery 12 for receiving at the office station indication current supplied to the line circuit at the field station according to the position of the crossover CV, the office station apparatus includes a circuit switching means which comprises relays WRP, WKR, LPS and LVP. The relays WKR, LPS and WRP are neutral relays, with relay WKR being provided with a selected slow release period, relay LPS being quick to pick up and slow to release, relay WRP being of the ordinary acting type. Relay LVP is a polar relay characterized by its polar contacts remaining closed in their last position when the relay is deenergized.

Normally the winding of the relay WKR is interposed in a connection between the line wires W1 and CL around the battery 12. This connection can be traced from line wire W1 over back contact 83 of relay LPS, back contact 84 of relay WRP, winding of relay WKR, and wire 85 to terminal C of battery 12, to which terminal the line wire CL is also connected. Since, as pointed out hereinbefore, the battery 13 at the field station is normally connected with this line circuit, it follows that the relay WKR at the office station is normally energized in series with the polarized relay WR at the field station. At such time as relay LPS is picked up, closing front contact 86, and relay WKR is released, closing back contact 87, the relay WRP is interposed in a connection for supplying current from battery 12 to this line circuit. When the polar relay LVP is set at its normal position in a manner to shortly appear, a connection extends from terminal B1 of battery 12 over normal polar contact 88 of relay LVP, winding of relay WRP, back contact 87 of relay WKR, front contact 86 of relay LPS and line wire W1. When the polar relay LVP is set to close its reverse polar contact 89, this connection is completed from the negative terminal N1 of battery 12.

Selection between the connection including relay WKR and the connection including relay WRP and the battery 12 is effected through the medium of relay LPS, the back contact 83 of relay LPS being interposed in the first mentioned connection and front contact 86 of relay LPS being interposed in the second mentioned connection. Relay LPS in turn is provided with a pick-up circuit which is closed during a movement of the switch lever 1L between its two positions N and R, and which circuit extends from terminal B1

75

of battery 12 over front contact 90 of relay WKP, contact 47—91 closed between the N and R positions of the lever 1L but open at both extreme positions of the lever, winding of relay LPS and terminal C. The relay LPS is also provided with a stick circuit, one branch path of which includes front contact 92 of relay WKP, resistance 93 and its own front contact 94, and a second branch path of which includes the terminal B1, back contact 95 of relay WRP, contact member 48 when lever 1L is at its normal position or contact member 49 when lever 1L is at its reverse position, back contact 96 of relay WKP, and then as before traced.

15 The polar relay LVP is selectively energized according to the position of the switch lever 1L, the arrangement being such that with relay LPS picked up, closing front contact 97, and lever 1L set at its normal position N to move contact member 45 to a corresponding position the lower winding 98 of relay LVP is supplied with current over a simple circuit easily traced, and the relay is energized at normal polarity to close its normal polar contacts 62 and 88, but when the lever 25 1L is moved to its reverse position R to move contact member 46 to a corresponding position the upper winding 99 of relay LVP is supplied with current and the relay is energized at reverse polarity to close its reverse polar contacts 63 and 89.

30 A normal indication lamp NL and a reverse indication lamp RL are disposed adjacent the switch lever 1L. An "inoperable" or approach lock indication lamp OS is also mounted at the lever 1L to indicate when, due to traffic conditions, the crossover cannot be controlled by the switch lever 1L. The immediate control of the lamps NL, RL and OS is effected by contact members 43 and 44 of the lever and the relays associated with the line circuit comprising wires W1 and CL. With the lever 1L at its normal position N, the lamp NL is illuminated by virtue of a circuit including terminal B1, back contacts 59 and 60 of the respective relays LPS and WRP, front contact 61 of relay WKP, normal polar contact 62 of relay LVP, contact member 43, lamp NL and battery terminal C. In the event the lever 1L is moved to its reverse position R, the lamp RL is illuminated over the same circuit up to front contact 61, and thence over reverse polar contact 63 of relay LVP, contact member 44, lamp RL and terminal C. When relay WKP is released in a manner to later appear, the lamp OS is illuminated over a circuit including back contacts 59, 60 and 64.

35 The office station apparatus is also provided with a circuit switching means governed by the signal lever 2L for at times connecting the battery 12 with the line circuit comprising line wires W2 and CL and to at other times provide this line circuit with a connection around the battery 12 for receiving at the office station an indication current supplied to the circuit at the field station. This circuit switching means comprises relays HRP, HKPS and HRPP, the relay HRPP being provided with a selected slow release period, relay HRP being quick to release and relay HKPS being of the ordinary acting type. With lever 2L moved to its RT position, a connection is completed from terminal B1 of battery 12 over contact member 55 of lever 2L, winding of relay HRP, back contacts 105 and 106 of relays HRPP and HKPS, respectively, and to the line wire W2, and current flows from terminal B1 of battery 12 over

the line wire W2 to the field station, through the winding of relay 2HR at the field station, and back to the office station over line wire CL, with the results that the relay HRP is energized in series with the polarized relay 2HR. Relay HRP, on picking up, closing front contact 107, completes a shunt path for this line circuit connection around the back contacts 105 and 106. When lever 2L is moved to its LT position, the terminal N1 of battery 12 is connected to the line circuit over the same connection, and relay HRP is energized and picked up in series with the polarized relay 2HR at the field station. For signal indication, the connection for line circuit including line wires W2 and CL around the battery 12 can be traced from wire W2 over back contact 100 of relay HRP, front contact 101 of relay HRPP, winding of relay HKPS, contact member 53 of lever 2L at its LT position or contact member 54 with lever 2L at its RT position, and wire 102. When relay HKPS is picked up, closing front contact 108, this last traced connection is completed around the front contact 101. The relay HRPP, the back contact 105 of which is interposed in the first connection associated with the line wire W2 and the front contact 101 of which relay is interposed in the second connection for this line circuit, serves to select between the two connections. Relay HRPP also serves to provide the so-called stick control for the signals governed by the lever 2L as will shortly appear. The relay HRPP is controlled over a pick-up circuit including front contact 109 of the relay HRP, and is provided with a stick circuit which includes the contact member 56 of the lever 2L, an emergency contact 111 and its own front contact 110.

30 Three signal indication lamps 112, 113 and 114 are mounted adjacent the lever 2L and are illuminated to indicate the position of the signals governed by this lever in a manner to be pointed out when the operation of the apparatus is described. The immediate control of lamp 112 includes back contact 115 of relay HKPS. Lamp 113 is illuminated when the lever 2L is moved to its LT position, and the front contact 116 of relay HKPS is closed. Lamp 114 is illuminated when the lever 2L is moved to its RT position and the front contact 116 of relay HKPS is closed.

35 Referring to the third line circuit comprising line wires W3 and CL, a connection is provided from positive battery terminal B1 when push button 2PB is depressed to close contact 57, and a connection is completed from negative terminal N1 of battery 12 when the push button 4PB is depressed, closing contact 58.

40 In describing the operation of the apparatus, I shall assume at the start that the crossover CV is normal, the associated signals are all at stop position, and the control levers at the office station are at their respective normal positions. Under this normal condition current of what I shall call normal polarity for indication is supplied from battery 13 at the field station to the line circuit including line wires W1 and CL so that the relay WKP is picked up and the relay WR is energized at normal polarity. It is to be noted that this current flows from terminal C of battery 13 over line wire CL to terminal C at station CO, wire 85, winding of relay WKP, back contacts 84 and 83, line wire W1, front contacts 65 to 70, inclusive, winding of relay WR, back contact 71, normal polar contact 72 and terminal 75

N¹ of battery 13. With relay WR thus energized, any creeping or false movement of the crossover CV away from its normal position will cause current to be again supplied to the switch machines SM1 and SM2 to restore the track switches. With relay WKP picked up, closing front contact 61, the normal lamp NL is illuminated to indicate the normal position of the crossover.

10 With the signal lever 2L at its normal position, the line circuit comprising the line wires W2 and CL is open, with the result that the polarized relay 2HR is normally deenergized to cause the signals controlled by this relay to be at the stop position. Also, the relay HKPS at the office station is deenergized, closing back contact 115, causing the lamp 112 to be illuminated to indicate at lever 2L the stop position of the associated signals. If the operator wishes to operate 15 the signal R2A to permit a train on track EB to move east (right) over the track section 2T, with the cross-over at its normal position, the signal lever 2L is moved to its RT position. Contact member 55 of relay 2L now completes a 20 connection from positive terminal B1 of battery 12 to the line wire W2, and current which I shall call positive or normal polarity, is supplied to this line circuit so that the relay HRP is picked up and the polarized relay 2HR is energized at 25 normal polarity. The picking up of relay HRP closes front contact 109, energizing the relay HRPP, and that relay on picking up opens at back contact 105 the connection to the line circuit, but this connection is maintained by virtue of a 30 path around back contact 105 which is closed at front contact 107 of relay HRP.

At the field station the energizing of relay 2HR at normal polarity selects the signal control relay R2AH and the signal R2A is operated to a 35 proceed position. When signal control relay R2AH picks up, opening back contact 31, the signal repeater relay R2P is deenergized and releases at the end of its slow release period. During the interval between the opening of front 40 contact 82 of relay R2P and the closing of its back contact 104, the line circuit is open and relay HRP at the office station is released to open at its front contact 107 the connection to battery 12 and to close at its back contact 100 the connection for this line circuit around the battery 45 12, it being recalled that relay HRP is quick acting. When the back contact 104 of relay R2P is closed, indication current flows from terminal C of battery 13 over line wire CL, wire 102, contact member 54, winding of relay HKPS, front 50 contact 101 of relay HRPP, back contact 100 of relay HRP, line wire W2, winding of relay 2HR, front contact 81 of relay L2P, back contact 104 of relay R2P and to the negative terminal N1 55 of battery 13. Relay HKPS is now picked up and relay 2HR is still energized at normal polarity since the indication current supplied to the line circuit from battery 13 flows through the winding of relay 2HR in the same direction as the control current supplied from battery 12 at 60 the office station. With relay 2HR still retained energized at normal polarity, the signal control relay R2AH is retained energized to operate the signal R2A. The picking up of relay HKPS to 65 open back contact 115 and to close front contact 116 causes the lamp 112 to be extinguished and the lamp 114 to be illuminated to indicate the proceed position of signal R2A. This indication circuit for signal R2A is retained until such time 70 as the train advances beyond the signal R2A 75

and opens the circuit for relay R2AH at the traffic controlled contact 16. With relay R2AH released to restore signal R2A to its stop position, the closing of back contact 31 completes the circuit for relay R2P, and that relay is reenergized and picked up with the result that the associated line circuit is restored to its normal open position and relays HKPS and 2HR are deenergized. The releasing of relay HKPS causes lamp 114 to be extinguished and the lamp 112 to be 10 illuminated to indicate the stop position of the signal. Since the relay HRPP is retained energized over its stick circuit, the associated line circuit is held open at back contact 105 of relay HRPP until such time as the lever 2L is restored to its normal position, and the stick circuit for relay HRPP is opened at contact member 56. It follows that signal R2A will not be again operated to a proceed position when the traffic controlled contact 16 is reclosed until the operator first returns the lever 2L to its normal position and then again moves the lever to its RT position. That is, the so-called stick control for the signal is effected by virtue of the stick circuit for relay HRPP. To remove such stick control for 15 the signal, the contact 111 would be set at its open position so that the relay HRPP is controlled by its pick-up circuit only.

In the event the signal L2 is to be operated to permit a train to move to the track section 2T in a west-bound direction, the signal lever 2L is moved to its LT position where contact member 55 completes the connection for the line circuit including line wire W2 to the terminal N1 of battery 12, and the relay HRP is picked up 20 and the polarized relay 2HR at the field station is energized at reverse polarity. The signal control relay L2H is now picked up to operate the signal and the repeater relay HRPP at the office station is energized. With relay L2H picked up 25 to operate the signal L2, the signal repeater relay L2P is deenergized and releases at the end of its slow release period. During the interval between the opening of front contact 81 of relay L2P and the closing of its back contact 103, the line circuit is open and the relay HRP is released 30 to disconnect the battery 12 from the line circuit and to complete the connection around battery 12 and which connection includes the relay HKPS. Current now flows from terminal B1 of battery 13 at the field station to the line circuit and the relays 2HR and HKPS are energized. Relay 2HR is still energized at reverse polarity 35 since the indication current supplied from battery 13 flows in the winding of the relay in the same direction as the control current supplied by battery 12 at the office station with the lever 2L at its LT position. When relay HKPS is picked up, the lamp 112 is extinguished and the lamp 113 is illuminated to indicate the proceed position of signal L2. When this train advances to the left of signal L2 and operates the traffic controlled contact 23, the signal relay L2H is deenergized and the signal L2 is restored to its stop position. The signal repeater relay L2P is now picked up 40 so that the associated line circuit is open and the two relays HKPS and 2HR are restored to their normal deenergized condition. The indication lamp 113 is now extinguished and the lamp 112 is illuminated to again indicate the stop position of the signal.

In the event the signal R2A should fail to respond to the picking up of the signal control relay R2AH in the manner previously described, the operator in order to operate the call-on sig- 45 50 55 60 65 70 75

5   **nal R2C** would depress the push button **2PB** for an interval to close the connection from terminal **B1** of battery **12** to the line wire **W3** for energizing the polarized relay **2-4CO** at normal polarity. The signal control relay **R2CH** is selected and is then retained energized over its stick circuit including the front contact **26** of the signal control relay **R2AH** with the result that the call-on signal **R2C** is operated.

10   As mentioned hereinbefore, the apparatus associated with the signal lever **4L** for controlling a polarized relay to operate the second mentioned set of right and left signals (signals **L4A**, **L4B** and **R4**) is omitted from the drawings since such apparatus and associated line circuits would be but a duplication of the apparatus and line circuits associated with the signal lever **2L**, and it is thought such duplication would not add to the understanding of the invention.

15   Starting again with the apparatus at its normal condition and assuming that the operator desires to reverse the crossover **CV**, the switch lever **1L** is moved to its reverse position **R**. During the inmovement of the lever **1L** between position **N** and position **R**, the contact member **47** engages contact **91** to complete the pick-up circuit for relay **LPS**, and this relay is picked up and is then retained energized by virtue of its stick circuit subsequent to the lever **1L** set at the full reverse position **R**. With relay **LPS** picked up, the line circuit including line wire **W1** is open so that both relays **WKP** and **WR** are deenergized and both are released at the end of their respective slow release periods. The slow release period of relay **WKP** is selected to be somewhat longer than the release period **WR** so that back contact **40** of relay **WR** is closed and relay **WKRP** is picked up prior to the release of relay **WKP**. Relay **WKRP** on picking up, opening back contact **71** and closing front contact **80**, disconnects the battery **13** from the line wire **W1** and completes the connection for relay **WR** to the line wire **CL** around battery **13**. With relay **LPS** picked up, closing front contact **97**, the relay **LVP** is energized at reverse polarity and its reverse polar contacts **63** and **89** are closed. On the next step in the operation, the relay **WKP** is released, closing back contact **87** to complete the connection from terminal **N1** of battery **12** to the line wire **W1**. Consequently, switch control current now flows from terminal **C** of battery **12** over line wire **CL** to the field station, front contact **88** of relay **WKRP**, winding of relay **WR**, contacts **65** to **70**, inclusive, back to the office station over line wire **W1**, front contact **86** of relay **LPS**, back contact **81** of relay **WKP** and to the negative terminal **N1** of battery **12** through the winding of relay **WRP** and reverse polar contact **89** of relay **LVP**. Relays **WR** and **WRP** are now both energized, the relay **WR** being energized at reverse polarity and relay **WRP** being picked up to close its front contact. With relay **WR** operated to its reverse position, the switch machines **SM1** and **SM2** are operated to move the track switches to their respective reverse positions.

65   When the polarized relay **WR** is operated to its reverse position, opening normal polar contact **38**, the relay **KR** is deenergized and released, closing back contact **41** so that the relay **WKRP** is retained energized after relay **WR** is operated. At the office station, the picking up of relay **WRP**

for relay WRP to the line wire W1 is still retained in effect subsequent to the release of relay LPS by virtue of the branch path including front contact 117.

When the movement of the crossover to its reverse position is completed, the relay KR is reenergized at reverse polarity and relay KR on picking up, opening back contact 41, deenergizes relay WKRP, which relay is released at the end of its slow release period. During the interval between the opening of front contact 80 and the closing of back contact 71 of relay WKRP, the line circuit is open and both relays WR and WRP are deenergized. Relay WRP, being quick to release, is released to disconnect the battery 12 from the line wire W1 and to complete at its back contact 84 the connection from line wire W1 through the winding of relay WRP and around the battery 12. The polarized relay WR, however, remains picked up by virtue of its slow release characteristics. When the back contact 71 of relay WKRP is closed, the connection from terminal B1 of battery 13 to the line wire W1 is completed and indication current is supplied to the associated line circuit. Since this indication current flows through the winding of relay WR in the same direction as the control current which energized the relay to operate it to its reverse position, the relay WR is retained at its reverse position. At the office station the relay WRP is reenergized and picked up. The lamp RL is now illuminated by virtue of its circuit completed at contact member 44, reverse polar contact 63 of relay LVP, front contact 61 of relay WRP and back contacts 60 and 59.

To move the crossover from its reverse position back to its normal position, the switch lever 1L is moved from its position R back to its position N. The operating steps following such a movement of the switch lever 1L are similar to those described in detail for moving the crossover to its reverse position and the description need not be repeated. It should be pointed out, however, that there is an "open" interval on the line circuit including line wire W1 following the picking up of relay LPS and prior to the release of relay WKP, because of the difference in the slow release periods of relays WR and WKP. During this interval the relay WKRP at the field station is operated to disconnect the battery 13 from the line circuit and to complete the connection around that battery. Then when relay WKP is released, a connection is completed at the office station for supplying control current from battery 12 to the line circuit according to the position of the lever 1L as reflected by the polar relay LVP. This control current operates the polarized relay WR to effect a corresponding movement of the crossover. Again when the movement of the crossover is completed, there is an "open" interval on the line circuit during the transfer from front contact 80 to back contact 71 of relay WKRP. During this interval the battery 12 at the office station is disconnected and a connection is completed for the line circuit around that battery. Subsequent to this last mentioned interval, indication current is supplied from battery 13 to the line circuit according to the position of the crossover, and this indication circuit affects the office station apparatus to establish an indication to indicate the position of the crossover.

In the case of the signal lever 2L and its associated line circuit, control current is supplied to the circuit in response to a movement of the 75

lever for operating the polarized relay 2HR for effecting a corresponding operation of the associated signal. When the corresponding signal is operated, there is an "open" interval on the line circuit, during which interval the office station battery is disconnected from the line circuit and a connection is completed for the circuit around the battery. Subsequent to such "open" interval on the line circuit, indication current 5 is supplied to the circuit from the field station battery to effect an indication at the office station for indicating the proceed position of the signal.

It should be pointed out that when the signal R2A, for example, is operated in the manner explained hereinbefore the corresponding approach locking contacts 65 to 68, respectively, are opened and open the line circuit for the polarized switch controlling relay WR. The relay WR is, however, retained energized over the local circuit including the corresponding back contacts 74 to 77. The relay WKP at the office station is deenergized and, on releasing to open front contact 61 and closing back contact 64, causes the normal switch indication lamp NL to be extinguished and the OS lamp to be illuminated. Illumination of lamp OS is an indication to the operator that the crossover cannot be operated by the lever 1L.

To describe the "lockout" feature of the present system, let it be assumed that the switch lever 1L is moved to its R position while the lamp OS is illuminated and the "lockout" is in effect. Because relay WKP is released, opening front contact 90, the relay LPS is not picked up in response to the movement of the lever 1L, and hence the sequence of operating steps that follow the picking up of relay LPS is not carried out. Let it be now assumed that traffic conditions which have opened the approach locking circuit change so that the line circuit for the relays WR and WKP is restored, the switch lever 1L still remaining at its reverse position. The crossover is not operated to a reverse position corresponding to the reverse position of the lever 1L since the relay LPS is not picked up because its pick-up circuit is held open at contact member 41. The lamps associated with the lever 1L are now all dark, and to regain control the operator must first restore the lever 1L to its normal N position so as to be in agreement with the crossover.

The unit principle provided by apparatus embodying my invention permits, as pointed out in the foregoing description, several different devices (switches and signals) to be each controlled and indicated over individual line circuits, and an unbalanced number of such devices when interrelated can be controlled and indicated with a minimum number of line wires extending between the control point and the location of the devices.

Although I have herein shown and described only one form of apparatus embodying my invention, it is understood that various changes and modifications may be made therein within the scope of the appended claims without departing from the spirit and scope of my invention.

Having thus described my invention, what I claim is:

1. In a remote control system, a field station and an office station, a controlled device at the field station operable to a normal and a reverse position, a control lever at the office station op-

erable to a normal and a reverse position, indication means at the office station operable to a normal and a reverse position, a polarized relay at the field station for selectively governing the positions of said device, an office station relay having a slow release period, two current sources one at each station, a two-wire line circuit extending between the two stations and normally having a winding of the polarized relay and a winding of the office station relay interposed therein means governed by said device to connect the field station source to said circuit to supply current of normal or reverse polarity according to the position of the device to energize said relays, means controlled jointly by said office station relay and said lever to selectively operate the indication means to indicate the position of said device, switching means operative in response to a movement of the lever between its two positions to open the line circuit for a period and to connect the office station source to the line circuit to supply current of normal or reverse polarity according to the position of the lever to correspondingly energize the polarized relay, and means at the field station responsive to such open period of the line circuit to complete a connection of the line circuit around the field station source.

2. In a remote control system, a field station and an office station, a controlled device operable to a given position, controlling means effective when energized to operate said device, a control lever at the office station operable to a given position, a two-wire line circuit extending between said stations and having a winding of said controlling means interposed therein, a source of current at each station, switching means at the office station controlled by the lever and operative in response to movement of the lever to its given position to open the line circuit for a period and to then connect the office station source to said circuit to energize said controlling means for operating the device, means at the field station controlled by the line circuit and responsive to such open period to complete a connection for the line circuit around the field station source, other switching means at the field station controlled by said device and operative in response to movement of the device to its given position to open the line circuit for a period and to then connect the field station source to the circuit, means at the office station controlled by the line circuit and operative in response to the last mentioned open period to complete a connection for the line circuit around the office station source, and a relay interposed in said last mentioned connection effectively energized by current supplied to the circuit at the field station for indicating the position of said device.

3. In a remote control system, a field station and an office station, a controlled device at the field station operable to a normal and a reverse position, controlling means responsive to the polarity of current supplied thereto for reversibly operating said device, a control lever at the office station operable to a normal and a reverse position, a two-wire line circuit extending between said stations and having a winding of said controlling means interposed therein, two current sources one at each station, switching means at the office station controlled by the lever and operative in response to a movement of the lever between its two positions to open the line circuit for a period and to then connect the office station

source to said circuit to supply according to the position of the lever current of normal or reverse polarity to the winding of said controlling means for effecting the corresponding operation of said device, means at the field station responsive to such open period of the line circuit to complete a connection of the line circuit around the field station source during the subsequent operation of the device, other switching means at the field station controlled by the device and operative in response to a movement of the device to open the line circuit for a period and to then connect the field station source to the line circuit to supply thereto according to the position of the device current of normal or reverse polarity, means at the office station responsive to such last mentioned open period of the line circuit to complete a connection of the line circuit around the office station source, and a relay interposed in said last mentioned connection effectively energized by the current supplied to the circuit at the field station for indicating the position of the device.

4. In a remote control system, a field station and an office station, a controlled device at the field station operable to a first and a second position, a polarized relay for reversibly operating said device, a controller at the office station operable to a first and a second position, a two-wire line circuit extending between said stations and having a winding of said relay interposed therein, a current source at each station, switching means at the office station controlled by the controller and responsive to a movement between its two positions to open the line circuit for a period and to then connect the office station source to the circuit to supply to the circuit according to the position of the controller current of normal or reverse polarity to energize the relay for effecting a corresponding operation of the device, means at the field station controlled by the line circuit and responsive to such open period to complete a connection for the line circuit around the field station source, other switching means at the field station controlled by said device and operative in response to a movement of the device to open the line circuit for a period and to then connect the field station source to the circuit to supply to the circuit according to the position of the device current of normal or reverse polarity, means at the office station controlled by the line circuit and responsive to the last mentioned open period to complete a connection for the line circuit around the office station source, another relay having a winding interposed in said last mentioned connection and energized by current supplied to the circuit at the field station, and indication means controlled jointly by said other relay and said controller.

5. In a remote control system for railroads, a track switch, a remote switch control lever having a position for each position of the switch, a polarized relay operative to govern the movement of the track switch to its normal and reverse positions, a two-wire line circuit extending between the track switch and the lever and having a winding of said relay interposed therein, two sources of current one adjacent the track switch and one adjacent the lever, circuit means controlled by the lever and operative in response to a movement of the lever between its two positions to open the line circuit for a period and to then connect the source at the lever to the line circuit to supply according to the position of the lever current of normal or reverse polarity to ener-

gize the polarized relay to effect a corresponding movement of the track switch, means controlled by the line circuit and responsive to such open period to complete a connection for the line circuit around the source at the switch, other circuit means controlled by the track switch and operative in response to a movement of the switch to open the line circuit for a period and to then connect the source at the switch to the line circuit to supply according to the position of the switch current of normal or reverse polarity, other means controlled by the line circuit and responsive to the last mentioned open period to complete a connection for the line circuit around the source at the lever, another relay having a winding interposed in said last mentioned connection and energized by current supplied by the source at the switch, and a normal and a reverse switch indicator selectively controlled by said other relay and the control lever.

6. In a remote control system, a field station and an office station, a controlled device at the field station having a normal and a reverse position, a polarized relay for selectively governing said device according to the polarity of current supplied to its winding, a control lever at the office station having a normal and a reverse position, a slow release relay and another relay at the office station, a two-wire line circuit extending between said stations and having the winding of said polarized relay interposed therein, two sources of current one at each of said stations for supplying current to said line circuit, means including a back contact of said other relay to complete a connection for the line circuit around the office station source and having a winding of the slow release relay interposed therein, circuit means at the field station controlled by said device to connect the field station source to the line circuit for normally energizing said polarized and said slow release relays, switching means controlled by said lever and operative in response to a movement of the lever to open the line circuit for the release period of the slow release relay and to then connect the office station source to the line circuit over a connection having a winding of said other relay interposed therein, said office station source connected to supply current of normal or reverse polarity according to the position of the lever to correspondingly energize the polarized relay for operating said device, means controlled by the line circuit responsive to such open period of the line circuit to complete a connection for the line circuit around the field station source, means controlled by said device and operative in response to a movement of the device to open the line circuit for an interval to deenergize said other relay and restore the connection including said slow release relay, and indication means governed by said slow release relay and said lever for indicating the position of said device.

7. In a remote control system for railroads, a stretch of track including a track switch, two signals one at each end of the stretch to govern traffic over the stretch, a switch control lever and a signal control lever at a remote office station, a first polarized relay for selectively governing the position of the track switch, a second polarized relay for selectively governing said signals, a first line circuit extending between said station and said stretch including a first control line wire and a common line wire and having a winding of said first polarized relay interposed therein, a second line circuit extending between the

station and the stretch including a second control line wire and the common line wire and having a winding of said second polarized relay interposed therein, a switch indication means and a signal indication means at the station, two sources of current one at the station and one adjacent said stretch, means controlled by the switch lever when operated to complete a connection for the first line circuit around the source at the stretch and to connect the source at the station to such circuit to supply current of normal or reverse polarity according to the position of the switch lever for energizing said first relay, means controlled by the switch when operated to complete a connection for said first line circuit around the station source and to connect the source at the stretch to such circuit to control said switch indication means, means controlled by the signal lever when operated to connect the source at the station to said second line circuit to supply current of normal or reverse polarity according to the position of the signal lever to energize said second relay, and means controlled by either signal when operated to complete a connection for the second line circuit around the station source and to connect the source at the stretch to such circuit to operate said signal indication means.

8. In a remote control system for railroads, a stretch of track including a track switch, two signals one at each end of the stretch for governing traffic over the stretch, a switch control lever and a signal control lever at a remote office station, a first polarized relay for selectively governing the operation of the track switch, a second polarized relay for selectively governing said signals, a first line circuit including a first control line wire and a common line wire extending between the station and the stretch and having a winding of said first relay interposed therein, a second line circuit including a second control line wire and said common line wire extending between the station and the stretch and having a winding of said second relay interposed therein, a switch indication means and a signal indication means at the office station, apparatus partly at the station and partly at the stretch operative by virtue of said first line circuit to energize said first relay for operating the track switch in response to a movement of the switch lever and to then operate the switch indication means in response to such operation of the switch, and other apparatus partly at the station and partly at the stretch operative by virtue of said second line circuit to energize said second relay for operating said signals in response to a movement of the signal lever and to then operate said signal indication means in response to such operation of the signals.

9. In a remote control system for railroads, a stretch of track including a track switch, two signals one at each end of the stretch for governing traffic over the stretch, a switch control lever and a signal control lever at a remote office station, a switch indication means and a signal indication means at said station, a first line circuit including a first control line wire and a common line wire extending between said station and said stretch, a second line circuit including a second control line wire and said common line wire extending between said station and said stretch, two sources of current one at the station and one at the stretch, apparatus partly at the station and partly at the stretch operative to selectively govern the position of said track switch by current supplied from the station source to said first line circuit in response to a movement of the switch lever and to then selectively govern the position of said switch indication means by current supplied from the source at the stretch to said first line circuit in response to the effected position of the track switch, and other apparatus partly at the station and partly at the stretch operative to selectively govern the position of said signals by current supplied from the station source to said second line circuit in response to a movement of the signal lever and to then selectively govern the position of said signal indication means by current supplied from the source at the stretch to said second line circuit in response to effected position of said signals.

10. In a remote control system for railroads, a track switch, a field station adjacent the switch, a remote office station, a polarized relay at the field station operative when energized to effect an operation of the track switch according to the polarity of the current supplied to the winding of the relay, a switch control lever at the office station having a normal and a reverse position, a two-wire line circuit extending between the two stations and having said relay winding interposed therein, switch indication means at the office station, two sources of current one at each station, apparatus partly at each station operative in response to a movement of the switch lever to supply to said circuit from the office station source current of a polarity corresponding to the position of the lever to energize said relay for effecting a corresponding operation of the track switch and to then in response to such operation supply to said circuit from the field station source current of the same polarity as that last supplied by the office station source to retain said relay energized and to effect a corresponding operation of said switch indication means.

EARL M. ALLEN.
